OR D 15,062

No. 15,062

June 17, 1884

UNITED STATES PATENT OFFICE.

EDWARD BOURNE, OF ALLEGHENY, PENNSYLVANIA.

DESIGN FOR A TOILET-CABINET.

SPECIFICATION forming part of Design No. 15,062, dated June 17, 1884.

Application filed May 26, 1882. Term of patent 7 years.

To all whom it may concern:

Be it known that I, EDWARD BOURNE, a citizen of the United States, residing at Allegheny, in the county of Allegheny and State of Pennsylvania, have invented and produced a new and original Design for Toilet-Cabinets, of which the following is a specification.

The leading feature of my design consists of a shield-shaped back piece showing a series of ornamental open-work baskets upon the face, and an ornamental base upon which it may stand.

In the accompanying illustration the figure represents a front view of my design.

The letter *c* indicates a shield-shaped back piece. Near the top and across the face of this shield is an oblong rack, which forms an ornamental cornice. Farther down, and on each side of the shield, are two open-work

cup-shaped baskets, *g g*, which form ornamental side appendages, and near the bottom of the shield is a smaller and oblong basket, *h*, which forms an ornament between the base and upper part of the shield.

The letter *k* indicates an ornamental base at the lower edge of the shield, having curved ornamental sides *l*, which face directly under the basket ornaments *g*.

I claim—

The design for a toilet-stand, as shown and described, the same consisting of the shield-shaped back piece having basket ornaments and the ornamental flanged base.

E. BOURNE.
